(57) **CLAIM**

The ornamental design for a floating net, as shown and described.

DESCRIPTION

FIG. 1 is an isometric view of a floating net.

FIG. 2 is a front view of the floating net of FIG. 1.

FIG. 3 is a right side view of the floating net of FIG. 1.

FIG. 4 is a rear view of the floating net of FIG. 1.

FIG. 5 is a left side view of the floating net of FIG. 1.

FIG. 6 is a top view of the floating net of FIG. 1; and,

FIG. 7 is a bottom view of the floating net of FIG. 1.

The broken lines form no part of the claimed design. The cross-hatched shading on the netting portion of the floating net shown in the figures represents the mesh texture of that netting.

The entire netting portion of the floating net has the mesh texture, however, for clarity in the figures, the cross-hatching is not shown uniformly across the entire netting portion of the floating net.
